US00D474151S

(12) **United States Design Patent** (10) Patent No.: **US D474,151 S**
(45) Date of Patent: ** May 6, 2003

(54) **PORTABLE BATTERY JUMPER**

(75) Inventors: **Chad James**, Taylors, SC (US);
Richard M. Hulden, Taylors, SC (US)

(73) Assignee: **Sunex International, Inc.**, Greenville,
SC (US)

(**) Term: **14 Years**

(21) Appl. No.: **29/167,406**

(22) Filed: **Sep. 13, 2002**

(51) LOC (7) Cl. **13-02**

(52) U.S. Cl. **D13/119**; D13/110

(57) **CLAIM**

The ornamental design for a portable battery jumper, as shown and described.

DESCRIPTION

FIG. 1 is an elevated perspective view of the present invention with certain features on the sides and the front shown in dashed line as environmental;

FIG. 2 is an elevated perspective view of the present invention with certain features on the sides and the back shown in dashed line as environmental;

FIG. 3 is a top plan view of the embodiment of FIGS. 1 and 2 with certain features shown in dashed line as environmental;

FIG. 4 is a left side plan view of the embodiment of FIGS. 1-3;

FIG. 5 is a front plan view of the embodiment of FIGS. 1-4; FIG. 6 is a right side plan view of the embodiment of FIGS. 1-5;

FIG. 7 is a rear plan view of the embodiment of FIGS. 1-6; FIG. 8 is a bottom plan view of the embodiment of FIGS. 1-7;

FIG. 9 is a rear plan view of an alternative embodiment of the design, with the other views being identical to FIGS. 1, 4-6 and 8;

FIG. 10 is a top plan view of the embodiment of FIGS. 1, 4-6, 8 and 9, with certain features shown in dashed line as environmental; and,

FIG. 11 is an elevated perspective view representing two additional alternative embodiments of the design, with the other views being identical to either FIGS. 2-8 without the spheroidal sections shown in FIGS. 2-8 or FIGS. 2, 4-6 and 8-10 without the spheroidal sections.

The broken lines throughout the drawings are included for the purpose of illustrating portions of the jumper that form no part of the claimed design.
